CLAIM

The ornamental design for a folding tripod, as shown and described.

DESCRIPTION

FIG. 1 is a front view of a folding tripod showing my new design, in a stowed configuration.

FIG. 2 is a back view of the folding tripod in a stowed configuration.

FIG. 3 is a top view of the folding tripod in a stowed configuration.

FIG. 4 is a bottom view of the folding tripod in a stowed configuration.

FIG. 5 is a left side view of the folding tripod in a stowed configuration.

FIG. 6 is a right side view of the folding tripod in a stowed configuration.

FIG. 7 is an upper perspective view of the folding tripod in a stowed configuration.

FIG. 8 is a lower perspective view of the folding tripod in a stowed configuration.

FIG. 9 is a front view of the folding tripod in an extended configuration.

FIG. 10 is a back view of the folding tripod in an extended configuration.

FIG. 11 is a top view of the folding tripod in an extended configuration.

FIG. 12 is a bottom view of the folding tripod in an extended configuration.

FIG. 13 is a left side view of the folding tripod in an extended configuration.

FIG. 14 is a right side view of the folding tripod in an extended configuration.

FIG. 15 is an upper perspective view of the folding tripod in an extended configuration.

FIG. 16 is a lower perspective view of the folding tripod in an extended configuration.

FIG. 17 is a front view of the folding tripod in an extended configuration with legs in a first position.

FIG. 18 is a back view of the folding tripod in an extended configuration with legs in a first position.

FIG. 19 is a top view of the folding tripod in an extended configuration with legs in a first position.

FIG. 20 is a bottom view of the folding tripod in an extended configuration with legs in a first position.

(Continued)

FIG. 21 is a left side view of the folding tripod in an extended configuration with legs in a first position.
 FIG. 22 is a right side view of the folding tripod in an extended configuration with legs in a first position.
 FIG. 23 is an upper perspective view of the folding tripod in an extended configuration with legs in a first position.
 FIG. 24 is a lower perspective view of the folding tripod in an extended configuration with legs in a first position.
 FIG. 25 is a front view of the folding tripod in an extended configuration with legs in a second position.
 FIG. 26 is a back view of the folding tripod in an extended configuration with legs in a second position.
 FIG. 27 is a top view of the folding tripod in an extended configuration with legs in a second position.
 FIG. 28 is a bottom view of the folding tripod in an extended configuration with legs in a second position.
 FIG. 29 is a left side view of the folding tripod in an extended configuration with legs in a second position.
 FIG. 30 is a right side view of the folding tripod in an extended configuration with legs in a second position.
 FIG. 31 is an upper perspective view of the folding tripod in an extended configuration with legs in a second position; and,
 FIG. 32 is a lower perspective view of the folding tripod in an extended configuration with legs in a second position.
